UNITED STATES PATENT OFFICE

CHARLES FRANCIS JENKINS, OF WASHINGTON, DISTRICT OF COLUMBIA

ALTIMETER

Application filed April 18, 1924. Serial No. 707,408.

This invention relates to that class of apparatus known as altimeters, and has for its distinguishing feature means for determining the distance to the ground from a flying machine in the air rather than the altitude of the plane above sea-level.

The usual altimeter is worthless when one is flying in mountainous country at night or in fog or snow, as it gives no warning at all 10 of the approach of a mountain.

The object of this invention is to warn the pilot of the approach of an obstruction, for example, a mountain, a forest or the like, and this is accomplished by the employment of 15 radio waves propagated in the plane and reflected from the obstruction, and the phase relation of the reflected to the succeeding propagated wave or waves at the source.

In the diagrammatic drawings herewith 20 Figs. 1, 2 and 3 illustrate the principle involved; and Fig. 4 one method of applying the same.

In Fig. 4 let S represent a radio sending machine, preferably having pronounced directional characteristics; R a receiving instrument, which may be tuned; and L a lamp lighted by the induction current of a 3-circuit coil 3CI. Any suitable low voltage lamp adapted to the strength of current induced 30 in the secondary or third coil may be employed. Both sending and receiving machines and the lamp are carried on the plane, the lamp perhaps on the instrument board of the plane.

Let it be explained that when the current in the sending coil (z) of 3CI is in phase with the current from the receiving coil (y) of 3CI, that the lamp L will burn at maximum brightness, and that when the current is out 40 of phase the lamp burns less brightly until when it is in opposition the light may go out entirely, a well known phenomena, of course.

To illustrate the operation of the device it may be assumed that the plane is flying 45 on the line A—A, one wave length above the ground at the moment. With the sending machine in operation, the wave reflected from the ground is also one wave length long, or a total of two wave lengths on its return 50 to the plane, where it is picked up by the re-

ceiving set. The wave frequency in coil z is, therefore, in phase with the frequency in coil y and the lamp burns brightly. This condition is shown in Fig. 1.

In Fig. 2 the plane has advanced to a position where the phase relation has been disturbed by reason of the rising ground M, and the light burns less brightly. Therefore the pilot is warned of a difference in the ground elevation and he "noses" his plane up. If 55 this makes the lamp burn brighter he is advised that the ground is rising, but also that he is rising faster. If the lamp should go out entirely the pilot would be advised that a mountain was rising in his path faster than 60 he is climbing, and he would pull his plane up still more sharply to maintain a brightly burning lamp, the indication of a safe elevation above the obstruction.

When the plane is safely over the obstruction the lamp gets more dim instead of brighter as the plane continues to rise, and the pilot flattens out.

By changing the wave length of the sending machine by the rotation of the dial f 75 (Fig. 4), and synchronously the dial g on the receiving machine, for example, by means of the belt h, to exactly one wave length, the height above the ground can be read directly 80 on the dial (assuming the dials to be calibrated in feet).

What I claim, therefore, is—

1. A safety device for an airplane for indicating its approach to an obstruction and comprising a sending set carried by the airplane and having pronounced directional characteristics for propagating radio waves of a length corresponding to the desired flight height of the airplane and adapted to be reflected back by the surface of the ground 85 to the airplane, a receiving set also carried by the airplane for receiving the reflected radio waves, and means connected with the sending and receiving sets for indicating when the propagated and reflected waves are 90 in and out of phase.

2. A safety device for an airplane for indicating its approach to an obstruction and comprising a sending set carried by the airplane and having pronounced directional 100

characteristics for propagating radio waves of a length corresponding to the desired flight height of the airplane and adapted to be reflected back by the surface of the ground to the airplane, a receiving set also carried by the airplane for receiving the reflected radio waves, and means connected with the sending and receiving sets for indicating when the propagated and reflected waves are in and out of phase, said means including a three circuit induction coil having its primary coils connected with the sending and receiving sets, and a lamp connected with the secondary coil of the third circuit induction coil.

In testimony whereof I have affixed my signature.

CHARLES FRANCIS JENKINS.
